PROCESS FOR THE PREPARATION OF
HIGHER ALKYL ESTERS OF THE CAR-
BOXYLIC ACIDSDonald J. Loder, Wilmington, Del., assignor to
E. I. du Pont de Nemours & Company, Wil-
mington, Del., a corporation of DelawareNo Drawing. Application May 25, 1933,
Serial No. 672,810

9 Claims. (Cl. 260—106)

This invention relates to a process for the preparation of the higher alkyl esters of the carboxylic acids and more particularly to the preparation of the higher alkyl esters of the aliphatic carboxylic acids from the lower alkyl esters thereof.

Esters are ordinarily prepared by direct esterification, that is by direct action of the acid on the alcohol. It is well known that esterification by the direct esterification process is extremely slow and particularly so when the higher acids are reacted with the higher alcohols. Furthermore, the higher alcohols to be used in the preparation of the higher alkyl esters are generally expensive which results in a product too costly for general use.

An object of the present invention is to provide a simple and economical process for the preparation of higher alkyl esters. Another object of the present invention is to provide a process for the preparation of the higher alkyl esters of the carboxylic acids from the lower alkyl esters of those acids. A further object of the invention is to provide a process for the preparation of the higher alkyl esters of the carboxylic acids by the steps of halogenating a lower alkyl ester of the acid, condensing the halogenated ester with an olefinic hydrocarbon, and finally dehalogenating the resulting higher alkyl ester. A still further object of the invention is to provide optimum conditions and highly efficient catalysts for use in carrying out such processes. Other objects and advantages of the invention will hereinafter appear.

I have found that the higher alkyl esters can be prepared readily and economically by halogenating the lower alkyl ester, condensing it with an olefinic hydrocarbon, and finally dehalogenating the resulting higher alkyl ester. A still further object of the invention is to provide optimum conditions and highly efficient catalysts for use in carrying out such processes. Other objects and advantages of the invention will hereinafter appear.

I have found that the higher alkyl esters can be prepared readily and economically by halogenating the lower alkyl ester, condensing it with an olefinic hydrocarbon, and finally dehalogenating the resulting higher alkyl ester. The ester-forming reaction apparently proceeds in accord with the following equations in which halogens other than chlorine may, of course, be used:

The compound designated as $RCOOR_1H$ in the halogenation reaction designated as Reaction (1) may have substituted for R any alkyl, aryl, or aralkyl grouping and R_1 any alkylene, arylene, or aralkylene grouping, while the X of Equation (2) designates any olefinic hydrocarbon. Thus, by the substitution of a methyl group for R and R_1 , and the olefine, ethylene, for X, propyl acetate is produced from methyl acetate:

Propylene and butylene similarly yield the butyl ester and amyl ester of acetic acid respectively. 15

Esters suitable for use in my process are readily available from a number of sources. They may be prepared from the primary, secondary, or tertiary alcohols by simple esterification, by ester interchange, or by any suitable process and include, for example, the alkyl esters of the aliphatic carboxylic acids generally, i. e. such esters as methyl, ethyl, propyl, butyl, and higher alkyl esters of acetic, propionic, butyric, and even the higher aliphatic acids such, for example, as oleic, 25

palmitic, stearic, and the like. It is to be understood that my process is primarily directed to the preparation of the higher alkyl esters, from the lower alkyl esters, and in lieu of condensing a high alkyl ester of acetic acid, such as ethyl acetate, with ethylene, in order to obtain a butyl ester, for example, I usually prefer to use a lower alkyl ester and react it with a higher olefine, for example the methyl ester with butylene to get the amyl ester. Nor do I limit myself to the 35 condensation of the olefine with the saturated esters, of the monocarboxylic acid for the unsaturated esters and polycarboxylic acid esters, for example methyl acrylate, ethyl acrylate, methyl citrate, ethyl tartrate and equivalent esters may 40 likewise be used, in accord with my invention, for the preparation of their corresponding higher esters. It is not essential that a single ester be condensed with an olefine to obtain a single 45 higher ester, for a mixture of esters may be used such as are obtained by esterification of the oxygenated organic compounds, principally alcohols, which are obtained by the catalytic hydrogenation of carbon oxides under pressure according to the process described by E. F. Izard in U. S. application Ser. No. 656,766. The product obtained by condensation of these esters in accord with 50 my process will give higher alkyl esters of this mixture of oxygenated organic compounds. Furthermore, aromatic esters, such, for example, 55

as methyl benzoate, ethyl toluate, may likewise be treated for the preparation of the higher esters of these aromatic carboxylic acid esters.

The olefines to be used will, of course, in each instance be determined by the number of carbon atoms desired in each alkyl group. Thus, for example, the olefines: ethylene, propylene, butylene, etc., may be employed as well as the diolefines, such as, for example, butadiene and isoprene. These olefines may be obtained from a number of sources; thus, ethylene and various homologues thereof, found in gases evolved in cracking petroleum, may be separated therefrom, by fractional liquefaction. It is preferable, for the sake of avoiding undesirable by-products, that the hydrocarbon it is desired to convert be employed in a relatively high degree of purity.

The halogenation of the lower alkyl ester may be carried out by any suitable halogenation process, for example by passing chlorine into the liquid ester at a suitable temperature and pressure, such, for example, as from 0° to the boiling point of the ester, which, of course, will be determined inter alia by the type of ester being halogenated. Usually, it is preferable to have present therein a suitable halogenation catalyst, such as ferric chloride or iodine. The halogenation is continued until the desired amount of chlorine or other halogen has been absorbed by the ester.

The condensation of the halogenated ester with the olefinic hydrocarbon may be conducted by dissolving in the halogenated product a suitable catalyst, such, for example, as ferric chloride, aluminum chloride, boron chloride, bismuth chloride, antimony chloride, boron fluoride, and equivalent catalysts, and into this mixture the olefine is introduced, preferably at a temperature of from 0° C. to 250° C. and under a pressure of from 1 to 100 atmospheres, although the temperature and pressure are governed, for optimum operating conditions, by the particular halogenated ester and olefine being reacted. A temperature of approximately 100° C. and a pressure of approximately 50 atmospheres have been found suitable for many condensations of this type.

Any suitable dehalogenation process may be employed for removing the halogen from the halogenated ester but usually I prefer to effect this dehalogenation by treating the halogenated ester with hydrogen under pressure, that is the liquid halogenated ester, at a temperature in the neighborhood of 150-350° C., is hydrogenated under a pressure of from 100-4000 lbs. per sq. in. in the presence of a suitable dehalogenating catalyst, such, for example, as that disclosed in H. R. Arnold U. S. appl. Ser. No. 690,570 filed September 22, 1933.

The following example will illustrate one method of practicing the invention, although the invention is not limited thereto:

Example.—Methyl acetate (into which 0.5% FeCl_3 may be incorporated as catalyst) is chlorinated at its boiling point until approximately 1 mole of chlorine for each mole of ester has been absorbed. The crude product without purification and with 5% by weight of bismuth chloride is treated with propylene under normal cylinder pressure at a temperature of 150° C. The crude product is fractionated to remove unchanged chloromethyl acetate. The chlorobutyl acetate may be distilled to purify it. In case it is desired to prepare butyl acetate, the crude product after removal of unchanged chloromethyl acetate is re-

duced with hydrogen at 3000 lbs. per sq. in. and 325° C. using a suitable reducing catalyst such as those described in the Arnold application supra. The product obtained is essentially n-butyl acetate in addition to some isobutyl acetate. Some butyl and isobutyl alcohols are generally formed. 5

From a consideration of the above specification, it will be realized that any process for the preparation of higher alkyl esters from the lower alkyl esters, which is effected by condensing a lower halogenated alkyl ester with an olefinic hydrocarbon will come within the scope of this invention without sacrificing any of the advantages derived therefrom.

I claim:

1. A process for the preparation of higher alkyl esters of the organic carboxylic acids from lower alkyl esters thereof which comprises halogenating a lower alkyl ester of an organic carboxylic acid, condensing the resulting halogenated ester 20 with an olefinic hydrocarbon, and dehalogenating the resulting halogenated higher alkyl ester.

2. A process for the preparation of higher alkyl esters of the organic carboxylic acids from lower alkyl esters thereof which comprises halogenating a lower alkyl carboxylic acid ester, condensing the thus halogenated ester with an olefine, 25 and dehalogenating the resulting halogenated higher alkyl ester.

3. A process for the preparation of higher alkyl esters of the organic carboxylic acids from the lower alkyl esters thereof which comprises halogenating a lower alkyl ester of an aliphatic carboxylic acid, condensing the thus halogenated ester with ethylene, and dehalogenating the resulting halogenated higher alkyl aliphatic carboxylic acid ester. 30

4. A process for the preparation of higher alkyl esters of the organic carboxylic acids from the lower halogenated alkyl esters thereof which 40 comprises condensing a lower halogenated alkyl ester of a carboxylic acid with an olefinic hydrocarbon, and subsequently dehalogenating the thus condensed halogenated ester.

5. A process for the preparation of higher alkyl esters of the organic carboxylic acids from the lower halogenated alkyl esters which comprises condensing a lower halogenated alkyl ester of an aliphatic carboxylic acid with an olefine, and 50 subsequently dehalogenating the resulting halogenated and condensed ester.

6. A process for the preparation of propyl acetate from methyl acetate which comprises halogenating methyl acetate, condensing the halogenated methyl acetate with ethylene, and 55 dehalogenating the halogenated propyl acetate thus obtained.

7. In a process for the preparation of higher alkyl esters of the organic carboxylic acids from the lower alkyl esters thereof the step which 60 comprises condensing a lower halogenated alkyl ester with an olefinic hydrocarbon.

8. In a process for the preparation of the higher alkyl esters of the organic carboxylic acids from the lower halogenated alkyl esters thereof the 65 step which comprises condensing the lower halogenated alkyl ester with an olefine.

9. In a process for the preparation of higher alkyl aliphatic carboxylic acid esters from the lower halogenated alkyl aliphatic carboxylic acid esters the step which comprises condensing a lower halogenated alkyl aliphatic carboxylic acid ester with an olefinic hydrocarbon. 70

DONALD J. LODER.
